BRAKE FOR STRAND-SERVING APPARATUS

Tillman T. Bunch, Ashland, Md., assignor to
Western Electric Company, Incorporated, New
York, N. Y., a corporation of New York

Application July 1, 1949, Serial No. 102,664

18 Claims. (Cl. 57—19)

1

This invention relates to brakes for strand handling apparatus, and more particularly to brakes for applying tension to strands being withdrawn from supply cops and for stopping the withdrawal of such strands.

In the manufacture of the electrical conductors for use in the communication arts, certain types of conductors are advanced longitudinally through a concentric serving machine to receive a helically applied covering of cotton or similar material. In such machines, a member revolving concentrically around the core withdraws a composite band of strand material from a supply cop positioned on a rotatable spindle, and serves it around the core.

The minimum speed of rotation of the spindle and the supply cop carried thereby due to the withdrawal of the strands from the cop is, in some cases, substantially greater than the speed of the strand serving member. Various means have been employed in the art to apply an automatically decreasing braking force to a cop so as to maintain constant tension on the strands as the serving operation proceeds from a full cop to an empty cop. However, heretofore no braking apparatus has been developed, which is designed to apply a substantially increased braking force to stop the cop simultaneously with the serving member when the serving member is stopped because of a broken strand or other defects in the serving operation.

An object of the invention is to provide new and improved brakes for strand handling apparatus.

Another object of the invention is to provide new and improved brakes for applying tension to strands being withdrawn from supply cops and for stopping the withdrawal of such strands.

A brake for strand handling apparatus which embodies certain features of the invention, comprises a rotatable spindle designed to carry a cop containing a supply of filamentary material, means for withdrawing the filamentary material from the cop and cause rotation of the cop, and braking means for retarding the rotation of the cop and spindle with a braking force corresponding to the combined weight of the cop and the spindle and thereby maintain a substantially constant tension on the filamentary material as it is withdrawn from the cop.

A clear understanding of the invention will be had in the following detailed description of a specific embodiment thereof, when read in conjunction with the appended drawings, in which:

Fig. 1 is a front elevation of a concentric type

2

serving machine embodying certain features of the invention;

Fig. 2 is an enlarged fragmentary, sectional view of a portion of the apparatus shown in Fig. 1;

Fig. 3 is a vertical, sectional view taken along line 3—3 of Fig. 1;

Fig. 4 is horizontal, sectional view taken along line 4—4 of Fig. 2;

Fig. 5 is a horizontal, sectional view taken along line 5—5 of Fig. 2;

Fig. 6 is an isometric view showing a half-section of a cop tube used with the apparatus shown in Fig. 1 in the manner shown in Fig. 4;

Fig. 7 is a vertical section taken along line 7—7 of Fig. 2, and

Fig. 8 shows a schematic wiring diagram of the electrical apparatus used to control the serving machine shown in Fig. 1, and also a schematic diagram of a compressed air circuit controlled by the electrical apparatus.

Referring now to the drawings and more particularly to Fig. 1, there is shown a concentric type strand serving machine which is arranged to operate in a vertical position and includes a heavy base 10 which is suitably secured to the floor and a shaft indicated generally at 11 suitably journaled in anti-friction bearings positioned in the base 10. The lower end of the shaft 11 is arranged to receive a pulley 12 which engages an endless belt 15, which belt in turn engages a pulley 16 driven by a motor 20. A cup 22 is secured to the upper end of the shaft 11 for rotation therewith and has a cop 23 positioned on a spindle 21 rotatably mounted on a portion of the spindle extending into the cup. The cop 23 contains two composite textile bands 24—24 wound thereon 180° apart in a predetermined pattern which permits easy withdrawal of the bands from the cop. Each band 24 contains a plurality of individual strands and is withdrawn from the cop and passed through a slot 27 provided in the cup 22, after which the individual strands 25—25 of the band are fanned out and pass around individual guides 28—28 secured on the cup to a strand guide 30 provided on the upper end of the shaft 11 which extends above the spindle 21. When the cup 22 is rotated by the motor 20, it withdraws the bands 24—24 from the cop and wraps the individual strands 25—25 thereof around a core 31 being advanced through a central bore 32 provided in the shaft 11 by a capstan 33, which also is driven by the motor 20 through a suitable gear reducer mechanism (not shown).

The core 31 (Fig. 1), after receiving the textile covering, shall be referred to as the insulated core 34. The core 31 is withdrawn from a supply reel 35, which is rotatably mounted in a suitable manner, and passes around an idler pulley 36 mounted on a heavy arm 37 pivotally mounted on the base 10, and a pulley 38 which directs the core 31 to the central bore 32 of the shaft 11. The arrangement of the pulley 36 on the heavy arm serves to maintain substantially uniform tension on the core 31 by cushioning the jerks on the core caused by variations in the unwinding diameter of the reel. The core 31 passes upwardly through the bore 32 of the spindle 11 and receives a textile covering at a point adjacent to the guide 30 to form the insulated core 34. The core 34 advances upwardly through a central bore 40 provided in a tubular cop storage post 41 which is held in a vertical position by a tubular post 42 secured to the base 10 in a suitable manner and around a pulley 43 to the capstan 33. After passing around the capstan several times, the insulated core 34 passes directly to a pulley 50 mounted on a suitable traversing apparatus 51 which serves to distribute the core 34 evenly on a takeup reel 52 rotatably mounted on a support 53 and driven by a motor 55.

A plurality of cops like the cop 23 (Fig. 1), are positioned in tandem over the cop storage post 41 so that the core 31 passes through the center aperture thereof in order that a full cop may be positioned on the spindle 21 when the cop originally positioned thereon is exhausted. A tubular member 57 is slidably positioned in the bore 40 of the post 41 and normally has a portion thereof which extends below the free end of the post 41 and passes through the central aperture of the lowermost cop 23 and thereby holds it in line with the advancing core 34. The member 57 is connected to a similar member 60 slidably positioned in the tubular post 42 by means of a cable 61. An arm 62 is hingedly mounted on the post 42 and is normally positioned to support the lowermost cop 23 a predetermined distance above the top of the cup 22. A second arm 63 is hingedly mounted on the post 42 for supporting the remainder of the cops 23-23 stored on the post 41. A pin 65 is secured to the member 60 and operates within a longitudinal slot 66 provided in the post 42. The member 57 is designed to be heavier than the member 60, in which case, the member 57 positions itself in the post 41 by its own weight so that the lowermost end thereof is adjacent to the guide 30. The pin 65 normally is positioned at the top of the slot 66 and by moving the pin downwardly to the bottom of the slot, the member 57 may be withdrawn from the lowermost cop and positioned entirely within the post 41.

The cup 22 rotates within a cylindrical housing 70 secured on the base 10 and provided with an arcuate sliding door 71 made of transparent material and arranged to be operable by the lever 72. A sensitive detector indicated generally at 75 is provided in the housing 70 for the purpose of stopping the cup 22 when one of the strands 25-25 breaks and also when the cop 23 is exhausted. The detector 75 includes an upright post 76 rigidly secured to the base 10 (Fig. 2), and a rod 77 rotatably mounted between supports spacedly secured to the post 76 one of which is indicated by the numeral 78 (Fig. 5). The ends of the rod 77 are provided with ball bearings, one of which is shown in Fig. 7 and indicated by the numeral 79. Each bearing 79

5 is positioned on a conical seat provided in a counterbore provided in each support so that the post may be turned by the application of very little force.

10 A cam 80 is secured on the end of the rod 77 adjacent to the support 78. The cam 80 is made of a tubular member having one side thereof flattened to engage a resilient operating arm 81 of a sensitive switch 82 which is secured on the support 78. A wire loop 86 is secured to the rod 77 in such a position that when the flat side of the cam 80 is in contact with the resilient arm 81, the wire loop 86 is positioned directly in the path of any of the strands 25-25 which break while they are being served on the core 31. When any of the strands 25-25 break while the cup is serving the strands in the core 31, the loose end of the broken strand hanging from the guide 30 flies outwardly due to centrifugal force acting thereon and strikes the wire loop 86 with sufficient force to turn the rod 77 in a clockwise direction as viewed in Fig. 5. This movement of the rod 77 actuates the resilient arm 81 sufficiently to operate the switch 82 which is electrically connected to immediately stop the cup 22 in a manner hereinafter to be described.

15 While the detector 75 is so arranged that a single strand will turn the rod 77, it must be so adjusted that it will not be operated inadvertently by the vibration of the apparatus or by the windage created by the revolving cup.

20 Air under pressure from a suitable supply (not shown) is conducted by a pipe 90 to a pressure regulating valve 91 from which the air under pressure passes to a solenoid-operated valve 92 and from the solenoid valve through a pipe 93 to an air control unit indicated generally at 95. The air then is directed from the air flow control unit 95 by a pipe 97 to a brake mechanism for the spindle 21.

25 The air flow control unit 95 comprises an air valve 100 mounted in an inclined position in a generally rectangular housing 101 so that a portion of the valve stem 102 thereof is positioned outside the housing to receive a hand wheel 103. A wheel 105 is keyed to a portion of the valve stem positioned within the housing 101 and is provided with a ring 106 about the periphery thereof which is made of rubber or other suitable friction material. A small synchronous motor 109 and gear unit 110 is secured to a support 111 pivotally mounted on a bracket 112 secured to the top of the housing 101. The output shaft of the gear unit 110 is provided with a drive pulley 115 which rests against the ring 106 provided on the wheel 105. When the motor 109 is energized, it rotates the pulley 115 which, in turn, drives the wheel 105 and thereby turns the valve stem 102 to change the opening of the valve 100. The hand wheel 103 assumes the full line position shown in Fig. 3 when the valve 100 is fully open. As the wheel 105 is turned by the motor 109 the shaft moves inwardly in the valve 100, and when the hand wheel 103 assumes the broken line position, the valve 100 is fully closed. A cover 117 encloses the motor 109 and is held in place on the housing 101 by a nut 118 which threadedly engages the end of a post 120 secured in the housing 101.

30 Referring to Fig. 2, it is noted that a ball bearing 122 is positioned between the upper end of the shaft 11 and an annular support 123 which is secured to the base 10. An annular member 125 is keyed to the shaft for rotation therewith

and has the upper face thereof undercut to receive the bottom of the cup 22 and to align the cup coaxially with the rotating axis of the shaft. The bottom of the cup 22 is secured between the upper face of the ring 125 and an annular cap 126 by a plurality of screws like the screw 127. The upper end of the shaft 11 is provided with a reduced body portion 128 which extends upwardly in the cup and has the spindle 21 rotatably mounted thereon by means of needle bearings like the needle bearing 129.

The spindle 21 consists of a tubular body portion 130 which engages the needle bearings 129-129 and a hub portion 131 formed integral therewith. The tubular body portion 130 of the spindle is provided with a plurality of longitudinal grooves 132-132 equally spaced about the periphery thereof and is designed to slidably receive a cop tube indicated generally at 133 on which the cop 23 is wound. The cop tube 133 is formed of two identical, elongated sections 134-134 of semi-circular cross-section one of which sections is shown in Fig. 6. Each section 134 of the cop tube is provided with an inwardly projecting longitudinal rib 137 centrally disposed between the edges thereof and an inwardly projecting rib 138 at each edge thereof. When two sections 134-134 are butted together to form the cop tube 133, the ribs 137-137 slidably engage the grooves 132-132 of the spindle 21 and the ribs 138-138 have a combined width which permits them to slidably engage diametrically opposed grooves in the spindle 21 when the cop 23 is positioned on the spindle (Fig. 4).

The cop tube 133 is designed to have an internal diameter larger than the diameter of the tubular body portion 130 of the spindle 21, in which case, the ribs 137-137 and 138-138 secure the tube 133 concentrically on the spindle 21 so as to leave an annular clearance between the spindle and the internal surface of the tube. The ribs 138-138 secure the sections 134-134 on the spindle 21 against transverse movement, in which case, the sections can not be separated until the cop tube is slid off the upper end of the spindle. The ribs 138-138 also are designed to hold the sections 134-134 on the spindle against the action of centrifugal force on the sections when the spindle is rotated by withdrawal of the bands 24-24 from the cop 23 by the cup 22.

The hub 131 of the spindle 21 is of such diameter that a predetermined minimum running clearance 141 is provided between the internal bore of the cap 126 and the periphery of the hub 131. The hub 131 has a flange 142 formed integrally therewith which is positioned in a counterbore 145 provided in the annular member 125. The counterbore 145 is of such diameter that a minimum running clearance 146 is provided between the periphery of the flange 142 and the counterbore 145. The underside of the flange 142 is provided with an annular groove 147 which is designed to receive a ring 148 made of felt or other suitable friction material. The spindle 21 is assembled on the upper end 128 of the shaft 11 with the needle bearings 129-129 so that the weight of the spindle causes the ring 148 to rest on the bottom of the counterbore 145 of the annular member 125.

The pipe 97 directs air from the air flow control unit 95 to a groove 150 provided around the inner bore of a ring 151 secured to the support 123. The groove 150 is arranged to communicate with an annular groove 152 provided in the periphery of the member 125, whereby air from

the pipe 97 passes into the groove 152 and upwardly through passages 155-155 into an annular chamber 156 provided between the underside of the cap 126 and the top surface of the flange 142 of the spindle 21. Minimum clearances, while not indicated in Fig. 2 of the drawings, are provided between the annular member 125 and the ring 151. A grease seal 160 is positioned in the counterbore 161 provided in the hub 131 of the spindle 21 and a plurality of springs 162-162 are positioned between the grease seal 160 and a cup-shaped ring 163 resting on a shoulder 164 provided on the shaft 11. The springs 162-162 are designed to offset some of the weight of the spindle 21 and the cop 23 so that the felt ring 148 bears against the bottom of the counterbore 145 of the driving member 125 with a predetermined force when the cop tube 133 is empty and exerts a braking force on the spindle when it is rotated by the withdrawal of the strands from the cop 23. When air is admitted to the annular clearance 156, in a manner hereinafter to be described, it forces the spindle downwardly and presses the ring 148 more forcibly against the bottom surface of the counterbore and thereby increases the braking force exerted on the spindle by the ring 148. Since running clearance is provided between the periphery of the flange 142 and the counterbore 145, a certain amount of the air admitted to the annular chamber 156 leaks through this clearance to the underside of the flange 142 and must be allowed to escape freely from this area in order to prevent it from interfering with the braking force exerted on the spindle by the ring 148. A plurality of holes 165-165 are provided around the hub 131 to permit this air to escape from the underside of the flange 142. The ring 163 is keyed for rotation with the spindle 21 by means of a pin 166 which is positioned in one of the holes 165 so that the inner end thereof engages a complementary recess provided in a portion of the ring 163 between the springs 162-162.

Fig. 8 shows a schematic wiring diagram for the electrical apparatus forming a part of the above-described serving machine in which terminals 170-170 may be considered as being connected to a suitable source of three-phase A. C. voltage. The motor 20, which drives the shaft 11 and the cup 22 secured thereto and the capstan 33 is connected across the terminals 170-170 in series with normally open contacts 171-171 provided on a contactor 172 and normally open contacts 174-174 provided on a second contactor 175. A resistor 177 is connected across each normally open contact 174. A three-phase solenoid indicated generally at 180, which is provided for operating the brake (not shown) of the motor 20, is connected directly across the terminals 170-170 in series with normally open contacts 181-181 of a relay indicated generally at 182.

The electrical apparatus for controlling the operation of the motor 20 and the solenoid 180 receives potential from busses 185 and 186 which are connected across the outside terminals 170-170 of the three-phase voltage supply. A step down transformer 187 has its primary winding 188 connected directly across the busses 185 and 186. The secondary winding 190 of the transformer has one side thereof connected directly to ground indicated at 191 and the other side thereof connected to ground 191 in series with a normally closed contact 192 of the sensitive switch 82 of the detector 75, a normally

open contact 193 arranged to be closed by the door 71 of the serving machine, and an operating coil 194 of a relay 195. An operating coil 197 of the relay 172 has one side thereof connected to the bus 185 in series with a normally open "start" contact 198 and a normally closed "stop" contact 200, and has the other side thereof connected to the bus 186 in series with a normally open contact 201 provided on the relay 195. A normally open contact 202 is provided on the relay 175 and is connected in parallel with the "start" contact 198. An operating coil 205 of the relay 175 is connected to a junction 206 provided in the connection between one of the contacts 174-171 and one of the contacts 174-174. The other side of the operating coil 205 is connected to the bus 186 in series with a normally open contact 207 provided on a time delay relay 210 and a normally open contact 211 provided on the relay 172.

An operating coil 212 of the relay 210 has one side thereof connected to the bus 185 in series with a normally open contact 213 provided on the relay 175 and has the other side thereof connected to the bus 186 in series with the contact 211 of the relay 172. A junction point 215 provided between the contact 213 and the coil 212 is connected to a junction point 216 provided between the "start" contact 198 and the "stop" contact 200, in which case, the "start" contact 198 is connected in parallel with the contact 213 of the contactor 175. An operating coil 217 has one side thereof connected to the junction 215 and the other side thereof connected directly to the bus 186. A solenoid 220, which is arranged to actuate the valve 92 has one side thereof connected to the bus 185 in series with a normally closed contact 221 of the sensitive switch 121 positioned in the control unit 95 and the other side thereof connected to the bus 186 in series with a normally closed contact 222 provided on the relay 182 and a normally closed push button contact 223. The motor 110 of the air flow control unit 95 has one terminal thereof connected to the bus 185 in series with the contact 221 and the other terminal thereof is connected to a reactance coil 226, which in turn, is connected to a junction point 227 provided in the connection between one of the contacts 171 and one of the contacts 174 of the relays 172 and 175, respectively.

The compressed air circuit for the serving machine also is shown schematically in Fig. 8 to correlate its operation with various electrical apparatus described in the wiring diagram. When the motor is energized to rotate the cup 22, the solenoid 220 is deenergized and closes the valve 92 so that no air is admitted to the control unit 95 or to the annular chamber 156 of the serving machine when the machine is operating. When the motor is deenergized for any reason, the solenoid is immediately energized to open the valve 92 to admit air under pressure from the valve 91 to the air flow control unit 95, which control unit regulates the rate at which the air is admitted to the annular chamber 156 between the cap 126 and the flange 142 of the spindle 21.

Operation

Let it be assumed that a cop 23 is positioned on the spindle 21 and that the cops 23-23 have been assembled on the post 41 as shown in Fig. 1. A core 31 is withdrawn from the supply reel 35 and passed around the pulleys 36 and 37 and then upwardly through the central bore 32 pro-

vided in the shaft 11 and through the central bore of the post 41 and around the pulley 43, around the capstan 33 several times to the pulley 50, to the takeup reel 52. When the core 31 has been threaded through the machine in this manner, each textile band 24 of the cop 23 is passed through its respective slot 27 in the cup 22, after which the individual strands 25-25 of each band are separated and pass around individual strand guides 28-28 to the guide 30 provided on the upper end of the spindle 21. The ends of the individual strands 25-25 are attached to the core 31 in a suitable manner. After the strands 25-25 of the bands 24-24 are secured to the core in this manner, the door 71 is closed, which in turn, actuates the normally open contact 193 to its closed position. When the contact 193 is closed, the operating coil 194 of the relay 195 is connected across the secondary winding 190 of the transformer 187, in which case, the relay is energized and closes the normally open contact 201.

Air under pressure is admitted to the pipe 90 and the valve 91 is adjusted to fix the air pressure at the desired value for the machine. Since the contacts 222 and 223 are closed, the solenoid 220 is energized and holds the valve 92 open, whereby the air under pressure passes through the valve 92 to the valve 100 of the air flow control unit 95 to the annular chamber 156 provided between the cap 126 and the flange 142 of the spindle 21.

Assuming that a full size cop 23 is positioned on the spindle 21, the hand wheel 163 is turned to position the valve 100 in its full open position, which is the full line position of the hand wheel 163 and the wheel 165 as shown in Fig. 3. When these adjustments have been made, the "start" contact 198 is actuated to its closed position, whereby the operating coil 197 of the relay 172 is connected across the busses 185 and 186. Energization of the coil 197 closes the normally open contacts 171-171, which in turn, connect the motor 20 across the terminals 170-170 in series with the resistors 177-177. Since the resistors are connected in the motor circuit, the motor is started on reduced voltage and accelerates slowly, whereupon it starts rotating the cup which serves the textile strands around the core 31 and drives the capstan 33 to advance the core through the apparatus. At the same time the energization of the coil 197 also closes the normally open contact 211. The closed contact 211 connects the operating coil 212 of the relay 210 directly across the busses 185 and 186, whereupon the coil 212 is energized and closes its normally open contact 207 after a predetermined period of time has expired. The closed contact 207 connects to the coil 205, the junction 206, and the bus 186, whereupon the coil 205 is energized and closes its normally open contacts 174-174 and 213. The closed contacts 174-174 shunt the resistors 177-177 from the motor circuit, whereupon full voltage is applied to the motor and it accelerates to full speed and in turn drives the cup 22 and the capstan 33 at full speed. As soon as the coil 205 of the relay 175 is energized to close the contact 213, the operating coil 212 is connected directly to the bus 185, whereupon the "start" button may be released. When the "start" button 198 was actuated to its closed position, the coil 217 of the relay 182 was energized simultaneously with the coil 197 of the relay 172, in which case, the solenoid 180 of the motor 20 was energized to release the brake at the same in-

stant that the relay 172 was energized to connect the motor 20 across the terminals 170-170. The solenoid 180 remains energized to hold the brake in its off position so long as the motor remains connected to the supply terminals 170-170 by the contacts 171-171 of the relay 172.

As soon as the relay 172 is energized to close the contacts 171-171, the motor 110 of the air flow control unit 95 is connected across the busses 185 and 186, in which case, the motor 110 is energized simultaneously with the motor 20. Therefore, as the motor 20 rotates the cup to serve the textile strands on the advancing core 31, the motor 110 turns the valve stem 102 slowly in a direction which decreases the opening of the valve 100. Since the contact 222 is opened upon the energization of the coil 217 of the relay 182, the solenoid 220 is deenergized when the motor 20 is energized and the valve 92 remains closed. As a result, air under pressure is not admitted to the air flow control unit 95 or the annular chamber 156 provided at the base of the spindle 21. Under these conditions the braking force of the ring 148 tending to retard the rotation of the spindle caused by the withdrawal of the strands from the cop carried thereby is due entirely to the weight of the cop plus the fixed weight including the weight of the cop tube 133 and the spindle 21.

When the serving operation commences with a full cop positioned on the spindle, the braking force applied to the spindle is directly proportional to the weight of the cop because the weight of the tube and the spindle is insignificant with respect to the weight of the cop 23. In other words, under these conditions the weight of the cop 23 bearing on the felt ring 148 sliding around the bottom of the counterbore 145 of the annular member 125 determines the tension produced in the strands 25-25 as they are served around the core 31 by the cup 22. The diameter of the cop 23, at the start of the serving operation produces a maximum leverage condition as the strands are withdrawn from the cop, and as a result, the braking force of the ring 148 tending to retard the rotation of the cop with respect to the cup, must be at its maximum value in order to provide a predetermined serving tension in the textile strands 25-25. The weight of the cop at the start of the serving operation is as its maximum value, in which case the pressure that the cop exerts downwardly on the friction ring 148 provides a braking force which is commensurate with the weight of the cop and thereby creates the required tension on the strands 25-25 at the start of the serving operation.

As the cup is rotated to withdraw the textile bands 24-24 from the cop 23 and serve them spirally around the core 31 to form the insulated core 34, the diameter of the cop is constantly decreasing and likewise, the lever arm at the point of the withdrawal of the strands is constantly decreasing.

Due to the fact that the lever arm of the unwinding diameter of the strands being withdrawn from the cop is constantly decreasing, it is necessary that the braking force exerted on the spindle by the ring 148 constantly decrease in proportion to the change in the lever arm in order to maintain uniform tension on the strands 25-25. As the strands are withdrawn from the cop 23, the downward pressure exerted on the ring 148 by the weight of the cop constantly is decreasing with the result that the braking force on the spindle consequently is decreasing. By virtue of this arrangement, the braking force on the spindle 21

decreases by an amount corresponding to the decrease in the weight of the cop 23 so that the tension on the strands 25-25 remains substantially uniform during the serving operation from a full cop to an empty cop.

When the size of the cop 23 is reduced to a point where the weight of the cop tube 133 and the weight of the spindle 21 exceeds the weight of the remaining portion of the cop 23 left on the cop tube, the downward pressure exerted on the ring 148 is determined by the combined weight of the cop and the spindle. The combined weight of the cop tube and spindle is a fixed value and does not change as the cop diminishes in size. The springs 162-162 positioned under the spindle offset a predetermined portion of the combined weight of the spindle and cop so that the weight of the cop 23 controls the tension on the strands 25-25 throughout a major portion of the serving operation. When the effective weight of the tube and spindle on the ring 148 due to the springs 162-162 exceeds that of a partially exhausted cop 23, the effective weight produces a downward pressure on the ring 148 which creates a tension on the strands 25-25 equal to the tension produced by the weight of the cop at the start of the serving operation. The cup continues to withdraw the strands from the cop 23 and serves them around the advancing core 31 until a loose thread, which was placed in the cop 23 when the cop was wound on the tube 133, is uncovered and flies outwardly due to centrifugal force and strikes the wire loop 86 of the detector 75. The loose thread strikes the loop with sufficient force to turn the rod 77 and cause the resilient arm 81 to actuate the operating button of the sensitive switch 82 and open its normally closed contact 192.

When the contact 192 is opened, the coil 194 is disconnected from the secondary winding 190 of the transformer 187, whereupon the coil is de-energized and allows the contact 201 to drop open. The opening of the contact 201 disconnects the coil 197 from the busses 185 and 186, whereupon the relay 172 drops open and deenergizes the relay 175 which in turn deenergizes the relay 210. As a result, the motor 20 and the solenoid 180 are deenergized to stop the motor and the cup 22 immediately. When the coil 217 is deenergized, the contact 222 recloses and connects the solenoid 220 to the bus 186. However, the motor 110 of the control unit 95, which was energized simultaneously with the motor 20, is arranged to close the valve 100 before the cop 23 is completely exhausted because when the cop is nearly exhausted the braking force on the spindle due to its weight is sufficient to stop the spindle 21 and prevents overrunning of the spindle with respect to the cup 22. Therefore, when the loose strand of an exhausted cop strikes the wire loop 86 and actuates the switch 82, the motor 110 has turned the wheel 105 to close the valve 100 and opens the contact 221 of the sensitive switch 121. The opening of the contact 120 disconnects the solenoid 220 from the busses 185 and 186 and allows the solenoid valve 92 to open before the contact 222 is reclosed. Since the valve 100 of the air flow control unit is fully closed before the valve 92 is allowed to open air under pressure from the solenoid valve 92 is not admitted to the annular chamber 156 when a loose thread strikes the wire loop 86 and actuates the switch 82. Therefore, the braking force exerted on the spindle 21 by the ring 148 due to its own weight, stops the spindle 75 which is rotating substantially faster than the

cup 22 practically simultaneously with the cup, whereby no overrunning of the spindle occurs with respect to the cup.

When the motor 20 is stopped by the brake, the capstan 33 is also stopped and the core 31 is not advanced through the shaft 11 and the strand guide 30. The tube 133 is slid off the end of the spindle and separated so that it may be removed from around the core 31. The arm 62 is moved out of position so that the lowermost cop 23 positioned on the post 41 may be lowered into the cup 22 and positioned on the spindle 21 as shown in Fig. 4. When this cop 23 is positioned on the spindle, the start button 198 is actuated to start the motor 20 and place the serving machine in operation in the manner described. This cop is served around the core 31 until the loose thread provided in the cop terminates the operation of the cup in the manner described hereinabove.

While the detector 75 serves to terminate the operation of the serving machine when the cop from which the textile bands are being withdrawn is nearly exhausted, the switch also acts to terminate the operation of the machine when one or more of the strands 25-25 break during the serving operation in the following manner:

Let it be assumed that a cop 23 is positioned on the spindle 23 and that the motor has been energized to rotate the cup and withdraws the bands 24-24 from the cop and serve the strands 25-25 around the advancing core 31. When the machine is operating in this manner, the solenoid 220 is deenergized and the valve 92 is closed so that air under pressure from the pipe 91 is not admitted to the air flow control unit 95. Under these conditions the weight of the cop 23 exerts sufficient force downwardly on the ring 148 to maintain a predetermined tension on the strands 25-25 as they are served on the advancing core.

Let it be further assumed that one of the strands 25-25 breaks after the machine has been in operation for a very short period of time with respect to that period of time required to serve a full cop on the core 31. A broken strand causes an imperfect serving on the core 31 and the machine must be stopped immediately after a break occurs in order that the loose ends of the broken strands may be tied together so that the remaining portion of the cop may be served on the core 31.

When one of the strands breaks, the cop 23 is rotating substantially faster than the cup 22 and is of such weight that a substantially greater braking force is required to stop the cop 23 simultaneously with the cup 22 to prevent overrunning of the cop.

From the time the serving operation was commenced until the break occurs in one of the strands, the motor 110 turns the valve stem 102 in a direction which gradually decreases the opening of the valve 100. The speed of rotation of the pulley 115 together with the diameter of the driving wheel 105 is arranged to turn the valve stem 102 at a rate which produces a decrease in the opening of the valve 100 in proportion to the constantly decreasing size and weight of the cop 23. When the strand breaks, it flies outwardly, in much the same manner as that described for the loose strand attached near the inner end of the cop, and strikes the wire loop 86 with sufficient force to turn the rod 77 and actuate the operating button of the switch 82 to open its normally closed contact 192 and deenergize the coil 194 of the relay 195.

As soon as the coil 194 is deenergized the con-

tact 201 drops open and deenergizes the relays 172, 175 and 182 to immediately stop the motor 20 as described. The contact 222 reduces and energizes the solenoid 220 which opens the valve 92 to admit air under pressure to the air flow control unit 95. Since the valve 100 is partially closed by an amount proportional to the decrease in the initial size of the cop 23, the air flow control unit admits air under pressure to the annular chamber 156 at a rate which builds up a pressure therein to increase the downward pressure on the ring 148 and thereby increases the braking force on the spindle 21 sufficiently to stop the spindle 21 and cop 23, carried thereby, simultaneously with the cup 22.

The pressure of the air admitted to the annular chamber 156 by the valve 100 is arranged to be supplied by the valve 100 at a rate which will exert sufficient pressure against the flange 142, while some of the air is escaping through the predetermined clearance 141 provided between the hub 131 and the internal bore of the capstan 126. The clearance 141 is designed to allow the air to escape from an annular chamber 156, at a predetermined rate of flow. The initial pressure of the air admitted to the valve 100 together with the size of the valve opening at the time one of the strands 25 breaks, is designed to admit air under pressure at a rate which is substantially greater than that at which it can escape from the annular chamber 156, so that the braking force on the spindle 21 will increase in accordance with the size of the cop to be stopped when the strand breaks.

Some of the air admitted to the annular chamber 156, when a broken strand occurs, escapes to the underside of the flange 142 of the spindle around the clearance 146 between the periphery of the flange and the counterbore 145 provided in the rotating member 125. To prevent this air which escapes to the underside of the flange 142 from interfering with the operation of the brake, the air is allowed to escape therefrom through a plurality of passages 165-165 provided in the hub 131 of the spindle.

While one or more of the strands 25-25 may break at any time during the serving operation from a full cop to an empty cop, air under pressure is admitted to the annular chamber 156 at a rate which creates air pressure therein commensurate with the size of the cop to be stopped simultaneously with the cup 22. The size of the cop 23 at the time the strand breaks determines the air pressure required to stop the cop, and since the opening of the valve 102 is constantly decreasing in size in proportion to the decrease in the size of the cop, the valve always is adjusted so that it admits the air under pressure to the annular chamber 156 at a rate which will provide the necessary pressure on the brake to stop the cop simultaneously with the cup. By controlling the rate of flow of air under pressure to the annular clearance in this manner, the additional braking force applied to the spindle by the air pressure is prevented from stopping the cop too soon, with respect to the cup, and thereby causing the overrunning of the cup, which would break the strands 25-25 being withdrawn from the cop. Likewise, this control of the air admitted to the annular chamber 156 prevents the increased braking force on the spindle, that occurs when a strand breaks, from being insufficient to stop the spindle and cop in time to prevent a substantial overrunning of the spindle, which may cause serious tangling of the

bands 24—24 inside the cup and breakage of the bands.

The above-described apparatus is particularly well-adapted to stop a supply cop of a concentric serving machine with a force determined by the size of the cop to be stopped when a strand breaks. However, this apparatus may be readily modified and adapted to suit various types of apparatus, where it is desirable to prevent overrunning of a rotating member from which one or more filamentary strands are being withdrawn at a substantially high rate of speed, without departing from the spirit and scope of the invention.

What is claimed is:

1. An apparatus for tensioning strand material being withdrawn from a supply cop, which comprises a vertically positioned shaft, a spindle rotatably mounted on the shaft and designed to carry a cop containing a supply of strand material, means rotatable about the shaft for withdrawing the filamentary material from the cop and cause rotation of the cop, means for rotating the strand withdrawing means at uniform speed, a brake element mounted on the spindle for retarding the rotation of the spindle with a braking force determined by the weight of the cop and the spindle and thereby maintaining a substantially uniform tension on the material as it is expended from a full cop to an empty cop, a detector positioned adjacent to the rotating cop and arranged to be actuated by the end of a broken strand carried by the withdrawing means, and means responsive to the operation of the detector by a broken strand for stopping the means rotating the withdrawing means and thereby terminate the withdrawal of the strand from the cop.

2. An apparatus for tensioning strand material being withdrawn from a supply cop of strand handling apparatus, which comprises a vertically positioned shaft, a spindle rotatably mounted on the shaft and designed to carry a cop containing a supply of strand material, rotatable means for withdrawing the filamentary material from the cop and cause rotation of the cop, means for rotating the strand withdrawing means, a brake element mounted on the spindle for retarding the rotation of the spindle with a braking force corresponding to the weight of the cop and the spindle and thereby maintaining a substantially constant tension as the material is expended from a full cop to an empty cop, a post rotatably mounted adjacent to the cop and having a wire loop thereon extending generally opposite to the direction of rotation of the cop, and a sensitive switch arranged to be actuated when the post is turned to stop the means rotating the strand withdrawing means, said post being so positioned that an end of a broken strand carried by the withdrawing means, said post being so positioned sufficient force to turn the post and actuate the sensitive switch and stop the withdrawal of the strand from the cop.

3. An apparatus for tensioning strand material being withdrawn from a supply cop of strand handling apparatus, which comprises a vertically positioned shaft, a spindle rotatably mounted on the shaft and designed to carry a cop containing a supply of strand material, means rotatable with respect to the cop for withdrawing the strand material from the cop and cause rotation of the cop, means for rotating the strand serving means to a uniform speed, means for applying a braking force to the spindle corresponding to the

weight of the cop and the spindle so as to maintain a substantially uniform tension on the material as it is withdrawn from the cop, means arranged to be actuated by the end of a broken strand for stopping the means rotating the strand serving means, and means for increasing the braking force applied to the spindle to stop the rotation of the spindle simultaneously when the serving means is stopped by a broken strand to prevent overrunning of the cop with respect to the serving means.

4. An apparatus for tensioning strand material being withdrawn from a supply cop provided on strand handling apparatus, which comprises a vertically positioned shaft, a spindle rotatably mounted on the shaft and designed to carry a cop containing a supply of strand material, means rotatable about the axis of the cop for withdrawing the strand material from the cop and cause rotation of the cop, means for rotating the strand withdrawing means at a uniform speed, a brake element provided on the spindle for retarding the rotation of the spindle as the strand material is withdrawn therefrom, said spindle being movable axially on the shaft so that the brake element applies a braking force to the spindle corresponding to the weight of the cop and spindle and thereby maintains a uniform tension on the strand material as it is expended from the cop, a detector positioned adjacent to the rotating cop and arranged to be actuated by the end of a broken strand, means responsive to the operation of the detector by a broken strand for stopping the means rotating the strand withdrawing means and thereby terminate the withdrawal of the strand material from the cop, and means for causing a fluid under pressure to urge the spindle downwardly on the shaft to increase the braking force exerted by the brake element on the spindle by an amount corresponding to the size of the cop to be stopped when the serving means is stopped by a broken strand in order to prevent overrunning of the cop with respect to the serving means.

45 5. An apparatus for tensioning a strand material being served around a continuously advancing core, which comprises a shaft vertically positioned adjacent to the advancing core, a spindle rotatably mounted on the shaft and designed to carry a cop containing a supply of strand material to be served around the core, means rotatable about the axis of the core for withdrawing the strand material from the cop and serving it spirally around the core and cause rotation of the cop, means for rotating the strand serving means at a uniform speed, a flange secured centrally on the shaft and having an annular chamber formed therein, said spindle having a flange secured thereon for rotation within the annular chamber, a brake element provided on the flange of the spindle so as to slidably engage the bottom of the annular chamber, said spindle being movable axially on the shaft so that the brake element retards the rotation of the spindle with a braking force determined by the weight of the cop and spindle and thereby maintains uniform tension on the strand material as it is expended from a full cop to an empty cop, a post rotatably mounted adjacent to the cop and having a wire loop thereon extending toward the cop, means including a sensitive switch arranged to be actuated when the post is turned to stop the means rotating the strand serving means, said post being positioned so that an end of a broken strand

carried by the serving means strikes the wire loop with sufficient force to turn the post and actuate the sensitive switch to terminate the withdrawal of the strand from the cop, and means for admitting a fluid under pressure into the annular chamber so as to exert a pressure on the upper surface of the flange on the spindle to increase the downward pressure on the brake element by an amount corresponding to the size of the cop to be stopped to stop the cop and spindle when the serving means is stopped by a broken strand in order to prevent over-running of the cop with respect to the strand serving means.

6. An apparatus for tensioning strand material being served around a continuously advancing core, which comprises a hollow shaft vertically positioned so that a core may be advanced therethrough, means for rotating the shaft, a spindle mounted on the shaft and designed to carry a cop containing a supply of strand material to be served around the core, means secured for rotation with the shaft for withdrawing the strand material from the cop and serving it spirally around the advancing core and for causing rotation of the cop at a rate of speed substantially greater than the speed of the serving means, means for applying a braking force to the spindle corresponding to the weight of the cop and the spindle so as to maintain a substantially constant tension on the material as it is withdrawn from the cop by the serving means, and means arranged to be actuated by a broken strand being carried around the core by the serving means for stopping the shaft rotating means, whereby the serving means is stopped when a strand breaks while it is being served on the core.

7. A broken strand detector for strand handling apparatus having a strand supply cop and rotating means for withdrawing the strand from the cop, which comprises a post rotatably mounted adjacent to the withdrawing means, an electrical circuit including means for controlling the rotating means withdrawing the strand from the cop, a sensitive switch positioned adjacent to the post for controlling the continuity of the electrical circuit, and means secured on the shaft for actuating the switch when the shaft is turned, and means provided on the shaft so as to be engaged by the end of a broken strand and turn the shaft, whereby the switch is actuated to effect a change in the electrical circuit which de-energizes the rotating means and stops the withdrawal of the strand from the cop.

8. An apparatus for detecting a broken strand being withdrawn from a strand supply cop by a member rotating about the cop, which comprises a post rotatably mounted adjacent to the cop, means provided on the post so as to be engaged by a broken strand to turn the post, and means arranged to be actuated when the shaft is turned to stop the withdrawal of the strand from the cop when a strand break occurs.

9. An apparatus for detecting a broken strand being withdrawn from a strand supply cop by a member rotating about the cop, which comprises a post rotatably mounted adjacent to the strand supply cop, a wire loop positioned on the post so that it extends toward the member withdrawing the strand from the cop, said loop being arranged to turn the post when it is engaged by the end of a broken strand carried by the strand withdrawing member, a sensitive switch arranged to be actuated when the post is turned by a broken strand, and means controlled by the sensitive switch for terminating the withdrawal

of the strand from the cop when a broken strand occurs.

10. An apparatus for tensioning a filamentary material being withdrawn from a supply cop, which comprises a support having an annular recess therein, a shaft positioned centrally on the support with respect to the recess, a spindle mounted rotatably on the shaft and designed to carry a cop containing a supply of filamentary material, said spindle having a flange positioned within the annular recess, means rotatable about the axis of the core for withdrawing the filamentary material from the cop and causing rotation of the cop, means for rendering the withdrawing means operative or inoperative, a brake element provided on the flange of the spindle for retarding the rotation of the spindle as the filamentary material is withdrawn therefrom, said spindle having a predetermined axial movement on the shaft whereby the brake element applies a braking force to the spindle corresponding to the combined weight of the cop and spindle and maintains a uniform tension on the filamentary material being withdrawn therefrom, and means for admitting a fluid to the annular recess when the strand withdrawing means is rendered inoperative so as to exert a pressure on the upper surface of the flange of the spindle, thereby urging said spindle downwardly on the shaft with a force sufficient to stop the rotation of the cop simultaneously with that of the withdrawing means.

11. An apparatus for tensioning a filamentary material being served around a continuously advancing core, which comprises a support having an annular chamber therein, a shaft vertically positioned on the support concentrically with respect to the chamber and adjacent to the advancing core, a spindle mounted rotatably on the shaft and designed to carry a cop containing a supply of filamentary material to be served around the core, means rotatable about the axis of the core for withdrawing the filamentary material from the cop and causing rotation of the cop, means for rendering the withdrawing means operative or inoperative, said spindle having a flange secured thereon for rotation within the annular chamber, a brake element provided on the flange of the spindle so as to slidably engage the bottom of the annular chamber, said spindle being movable axially on the shaft so that the weight of the cop and the spindle on the brake element causes it to retard the rotation of the spindle with a braking force proportional to the weight of the cop and spindle and thereby maintains uniform tension on the filamentary material as the material is expended from a full cop to an empty cop, resilient means mounted in the annular chamber to urge the spindle upwardly and partially offset the weight of the spindle so that the pressure on the brake element due to the spindle maintains a tension on the material when the cop is substantially exhausted equal to the tension created by a full cop, and means for admitting a fluid into the annular chamber when the withdrawing means is rendered inoperative so as to exert a pressure on the upper surface of the flange on the spindle, thereby urging said spindle downwardly on the shaft to cause the brake element to apply a force sufficient to stop the cop and spindle simultaneously with the withdrawing means.

12. An apparatus for tensioning a filamentary material being served around a continuously advancing core, which comprises a rotatable hollow

shaft vertically positioned so that the core may be advanced longitudinally therethrough, means for rotating the shaft, a tubular spindle mounted rotatably on the shaft and designed to carry a cop containing a supply of filamentary material to be served around the core, means rotated by the shaft for withdrawing the filamentary material from the cop and causing rotation of the cop at a rate of speed substantially faster than that of the withdrawing means, a brake element secured to the spindle for retarding the rotation of the spindle with respect to the withdrawing means, said spindle being movable axially on the shaft so that the combined weight of the cop and the spindle exerts a downward pressure on the brake element and causes it to apply braking force to the spindle proportional to the combined weight of the cop and the spindle whereby a uniform tension is maintained on the filamentary material as it is expended from a full cop to an empty cop, means for rendering the withdrawing means operative or inoperative, and fluid actuated means operable when the strand withdrawing means is rendered inoperative for urging the spindle downwardly on the shaft with a force corresponding to the size of the cop at that time to cause the brake element to stop the rotation of the cop simultaneously with the withdrawing means.

13. An apparatus for tensioning a strand material being served around a continuously advancing filamentary core, which comprises a hollow shaft vertically positioned so that the core may be advanced longitudinally therethrough, a flange having an annular recess therein secured to the shaft, means for rotating the shaft, a spindle mounted rotatably on the shaft and designed to carry a cop containing a supply of strand material to be served around the core, a cup secured coaxially on the flange for rotation with the shaft, said cup being designed to withdraw the filamentary material from the cop and serve it spirally around the advancing core and cause rotation of the cop with respect to the flange, means for rendering the shaft rotating means operative or inoperative, said spindle having a flange whose periphery rotatably engages the walls of the annular recess, a brake element secured on the side of the flange adjacent to the bottom of the chamber, said spindle being movable axially on the shaft so that the combined weight of the cop and spindle presses the brake element against the bottom of the annular recess and causes it to exert a braking force on the spindle corresponding to the combined weight of the cop and the spindle and thereby maintaining a uniform tension on the filamentary material as it is expended from a full to an empty cop, and means operable when the shaft rotating means is rendered inoperative for admitting a fluid to the annular chamber under a pressure corresponding to the weight of the cop at that time so as to exert a pressure on the upper surface of the flange of the spindle, thereby urging said spindle downwardly to cause the brake element to stop the cop when the cup is stopped.

14. An apparatus for tensioning a filamentary material being served around an advancing continuous core, which comprises a hollow vertical shaft through which such a core may be advanced longitudinally, a flange having an annular chamber therein secured centrally on the shaft, means for rotating the shaft, a tubular spindle mounted rotatably on the shaft and designed to carry a cop containing filamentary ma-

terial to be served around the core, a cup secured to the flange for rotation therewith, means provided on the cup for withdrawing the filamentary material from the cop and serving it spirally around the core and causing rotation of the cop, said withdrawal of the material from the cop causes it to rotate, at a rate of speed substantially faster than that of the cup driven by the shaft, means for rendering the shaft rotating means operative or inoperative, said spindle having a flange positioned within the annular chamber so that its periphery slidably engages the walls of the chamber, a brake element secured on the flange adjacent to the bottom of the annular chamber, said spindle being movable axially on the shaft so that the combined weight of the cop and the spindle urges the brake element against the bottom of the annular chamber and causes it to exert a braking force on the spindle corresponding to the combined weight of the cop and spindle as the serving operation proceeds from a full cop to an empty cop, means operable when the shaft rotating means is rendered inoperative for admitting air under pressure to the annular chamber so as to exert a pressure on the upper surface of the flange on the spindle, thereby urging the spindle downwardly on the shaft to increase the pressure on the brake element, and means for controlling the pressure of the fluid in the annular chamber in accordance with the weight of the cop to be stopped at that time so that the brake element stops the cop simultaneously with the cup.

15. An apparatus for tensioning strand material being withdrawn from a supply cop, which comprises a vertically positioned shaft, a spindle rotatably mounted on the shaft and designed to carry a cop containing a supply of strand material, means for withdrawing the strand material from the cop and causing rotation of the spindle and the cop, means for applying a braking force to the spindle determined by the weight of the cop and the spindle and thereby maintaining a uniform tension on the material as it is expended from a full cop to an empty cop, a detector arranged to be actuated by a strand traveling outside its normal path of travel around the cop, and means responsive to the operation of the detector for stopping the withdrawal of the strand from the cop.

16. An apparatus for tensioning filamentary material being withdrawn from a supply cop, which comprises a support, a shaft vertically positioned on the support, a spindle rotatably mounted on the shaft and designed to receive a cop containing a supply of filamentary material, means rotatable about the shaft for withdrawing the filamentary material from the cop and causing rotation of the cop, a brake element mounted on the spindle so as to slidably engage the support, said spindle being movable axially on the shaft so that the combined weight of the cop and the spindle causes the brake element to apply a braking force on the spindle corresponding directly to the weight of the cop and the spindle as the material is expended from the cop, a detector positioned on the support so as to be actuated by filamentary material extending outside its normal path of travel around the cop, means responsive to the operation of the detector for stopping the withdrawing means, and means operable when the withdrawing means is stopped by operation of the detector for stopping the cop simultaneously with the withdraw-

ing means to prevent overrunning of the cop with respect to the serving means.

17. An apparatus for tensioning a strand material being withdrawn from a supply cop, which comprises a vertically positioned shaft, means for rotating the shaft, a support secured centrally on the shaft and having an annular chamber therein, a spindle mounted rotatably on the shaft and designed to carry a cop containing a supply of strand material, a cup surrounding the cop and secured for rotation with the shaft for withdrawing the strand material from the cop and causing the rotation of the cop, said spindle having a flange whose periphery engages the walls of said annular chamber, a brake element secured on the flange so that it engages the bottom of the annular chamber, said spindle being movable axially on the shaft so that the combined weight of the cop and spindle causes the brake element to exert a braking force on the spindle corresponding to the combined weight of the cop and spindle and thereby maintains uniform tension on the strand material as it is expended from the cop, a post mounted rotatably adjacent to the cup and having a wire loop extending outwardly toward the cop, a sensitive switch arranged to be actuated when the post is turned, said switch being arranged to control the continuity of an electric control circuit for rendering the shaft rotating means operative or inoperative, said post being so positioned that a strand extending beyond its normal path around the cop strikes the wire loop with sufficient force to turn the post and actuate the sensitive switch and terminate the withdrawal of the strand material from the cop, means for introducing a fluid under pressure to the annular chamber so as to exert a pressure on the upper surface of the flange on the brake element thereby urging the spindle downwardly, means for controlling the pressure of the fluid admitted to said annular chamber, and timing means started simultaneously with the strand withdrawing means for regulating the fluid pressure controlling means so that the fluid admitted to the annular chamber varies the braking force applied to the spindle by the brake element by an amount corresponding to the size of the cop to be stopped

when a strand actuates the sensitive switch in order to prevent overrunning of the cop with respect to the cup.

18. A brake for tensioning strands withdrawn from a supply cop provided on strand handling apparatus, which comprises a support, a shaft vertically positioned on the support, a spindle rotatably mounted on the shaft and designed to carry a cop containing a supply of strand material, means rotatable about the cop for withdrawing the material from the cop and causing rotation of the cop, means for rendering the withdrawing means operative or inoperative, a brake element mounted on the spindle so as to engage the support, said spindle being free to move axially on the shaft so that the combined weight of the cop and the spindle causes the brake element to retard the rotation thereof with a force corresponding directly to the weight of the cop and thereby maintain constant tension on the material as it is expended from a full cop to an empty cop, a detector arranged to be actuated by a strand extending outside its normal path of travel with respect to the withdrawing means, means responsive to the operation of the detector for stopping the strand withdrawing means, and fluid actuated means for urging the spindle downwardly on the shaft so as to increase the braking force exerted by the brake element on the spindle sufficiently to stop the cop simultaneously with the strand withdrawing means.
